FIG. 1

Des. 193,268

PAGE 2

FIG. 2

FIG.3

FIG. 4

FIG. 5

FIG. 1 is a view showing the top of a magnetic sound recording and reproducing instrument embodying my new design;

FIG. 2 is a perspective view showing the top, the front and the left side thereof;

FIG. 3 is a perspective view showing the rear and right side thereof;

FIG. 4 is an elevational view showing the left side thereof; and

FIG. 5 is a plan view showing the bottom thereof.

The dominant features of my new design are shown in the solid lines of the drawing. The holes in the ventilator fragmentarily shown in FIGS. 1 and 5 are uniformly distributed across the ventilator.

This application is a continuation-in-part of my pending application Serial Number D. 58,546 filed December 4, 1959, which is now abandoned.

I claim:

The ornamental design of a magnetic sound recording and reproducing instrument, as shown and described.
